UNITED STATES PATENT OFFICE.

WESTON M. FULTON, OF KNOXVILLE, TENNESSEE, ASSIGNOR TO THE FULTON COMPANY, OF KNOXVILLE, TENNESSEE, A CORPORATION OF MAINE.

VENTILATING DEVICE.

1,358,193.

Specification of Letters Patent. Patented Nov. 9, 1920.

Application filed August 31, 1916. Serial No. 117,871.

To all whom it may concern:

Be it known that I, WESTON M. FULTON, a citizen of the United States of America, and a resident of Knoxville, Tennessee, have 5 invented a new and useful Improvement in Ventilating Devices, which invention is fully set forth in the following specification.

This invention relates to a ventilating device, and particularly to the provision of a 10 portable, self-contained, automatic device for ventilating a room.

An object of this invention is to provide a ventilating device, which is compact, readily portable, and so shaped and constructed 15 as to enable its ready location at an aperture provided by an open window. A further object of this invention is to provide a device of the type characterized which is self-contained, and which will automatically regulate the degree of ventilation to the end of maintaining a substantially uniform temperature in a room. Still further objects of the invention relate to the provision of a ventilating device which is simple in construction, inexpensive to manufacture, easily installed, and efficient in 20 25 30 35 40 45 50 55 60 65 70 75 80 85 90 95 100 105 operation.

Stated briefly, the invention comprises a frame shaped to be positioned at the aperture provided by an open window, such frame providing an air passage therethrough, a damper device for controlling the flow of air through said passage, and thermosensitive means carried by the frame 35 for controlling said damper device, said frame and the parts carried thereby constituting a complete, automatic ventilating unit.

The invention is susceptible of embodiment in a variety of mechanical forms, two of which, for the purpose of illustration, have been shown on the accompanying drawings. But it is to be expressly understood that the drawings are for purposes 45 of illustration only, and are not to be construed as a definition of the limits of the invention, reference being had to the appended claims for that purpose.

Referring to the drawings, wherein the 50 same reference characters designate corresponding parts in the several figures,

Figure 1 is a perspective elevation, partly broken away, illustrating an embodiment of the present invention;

Fig. 2 is a horizontal section through the 55 structure of Fig. 1;

Fig. 3 is a vertical cross section taken through the inclosure containing the thermosensitive means;

Fig. 4 illustrates another embodiment of 60 the invention and is an elevation, partly in section, of one end of a frame of the type illustrated in Fig. 1, but showing the thermosensitive means in a compartment in said frame;

Fig. 5 is a vertical section through a window showing the ventilating device in position; and

Fig. 6 is an elevation of the window showing the ventilating device in position. 70

Referring in detail to the drawings, 1 represents a frame adapted to be positioned in a window casing at the aperture provided by an open window. This frame may be constructed in any suitable manner, the 75 embodiment illustrated comprising a rectangular box-like housing provided with a lagged top 2, an open rear face 3, and a front face shown as closed by any preferred form of grill 4.

Mounted within this frame 1 is a damper device adapted to control the flow of air through the passage provided by the interior of the frame. Any suitable form of damper device may be employed. In the 85 embodiment illustrated a plurality of shutters 5 are severally mounted by vertical pivots 6 to open and close the passage provided by the box-like frame 1, said shutters being each provided with an arm 7 pivotally 90 connected to an operating bar 8.

Means are provided for automatically controlling the above-described damper device to regulate the flow of air through the ventilating device in accordance with the 95 needs of the room, in a window of which the device is positioned, as determined by the temperature of this room. In accordance with the present invention, this automatic means comprises a thermosensitive device 100 connected with the damper device for actuating the same, carried by the frame either inside or outside the same, and positioned at the inner side of the window that it may be subjected to the air within the room to 105 respond to the changes in temperature thereof. In the form shown in Fig. 1, this thermosensitive means is illustrated as com-

prising an expansible and collapsible vessel 9 charged with a volatile thermosensitive fluid and mounted in position in any convenient manner, as by a bracket 10 which 5 holds one end wall of the vessel 9 fixedly in position. The opposite movable end wall 11 of said vessel is provided with a stem 12 engaging a lever 13 pivotally mounted at 14. The opposite end of said lever 13 has 10 pivotally connected therewith a link 15, which link is, in turn, pivotally connected with the heretofore described operating bar 8.

Means are preferably provided for adjusting the thermosensitive means to predetermine the initial temperature at which the same shall begin to respond to temperature changes to operate the damper device. In the form shown, an adjustable 15 spring is connected to the lever 13 to oppose movement of the movable end wall 11 of the vessel 9. To this end, lever 13 is provided with a laterally extending arm 16 to the outer end of which is connected one 20 end of a coil spring 17, the opposite end of this spring being carried by a block 18 mounted upon a screw-threaded spindle 19. Said spindle 19 extends to a position where it may be manually operated at will, the 25 same being shown as provided with a squared end 20 which may be engaged by an operating handle. Block 18 is preferably provided with a pointer member 21 shown as extending through a slot in the 30 casing 22 which is desirably provided for protecting the thermosensitive means from injury. The exterior of the casing 22, adjacent the slot in the side thereof may conveniently be provided with indicia whereby 35 the spring 17 may be readily set to obtain a predetermined initial actuation of the damper device. When a casing 22 is provided for surrounding the thermosensitive means, it should be so constructed as to readily 40 admit air from the room to such thermosensitive means, as by providing its walls with a plurality of apertures as illustrated in Fig. 1.

In the form shown in Fig. 4 the expansible and collapsible vessel 9 is mounted on a bracket 10' positioned within a compartment provided by a partition 23 near one end of the frame. Air at room temperature has free access to the thermosensitive device 50 through the apertures in the grill 4 (see Fig. 6) covering said compartment. The stem 12 attached to the movable end wall of the vessel 9 is shown as operating upon a bell-crank lever 13' having the damper-operating link 15' connected to one arm thereof, and the adjustable spring 17 connected to the other arm thereof. In this case the pointer 21' will be so bent as to extend to a 55 position where it may be readily seen from the front of the casing.

Any suitable means may be employed with either embodiment of the invention for mounting the frame 1 in operative relation to the window. A convenient construction, illustrated on the drawing, comprises angle-irons 24 provided in one flange with apertures 25 by which the same may be attached to the window jamb 26 by screws 27, as 70 illustrated in Fig. 6, and provided in the other flange thereof with elongated apertures 28 by which the same may be attached adjustably to the end walls of the frame 1 by screws 29. To prevent the leakage of air 75 between the window-sash 30 and the top of the frame 1, which would adversely affect the operation of the thermosensitive device, the upper edge of the rear face of said frame is preferably provided with a strip of felt, rubber or other suitable material 31, whereby the frame 1 will make an air-tight connection with the window-sash, while still 80 permitting the ready raising and lowering of the latter.

To install the ventilating device, the angle-irons 24 are attached by screws 27 to 90 the window jamb in such position that the frame 1 is supported on the window-sill 32. Screws 29 are then loosened, and the frame 1 is adjusted until the strip 31 snugly engages the window-sash 30, when raised as 95 shown in Fig. 5. Thereafter, the screws 29 are tightened, securely retaining frame 1 in its adjusted relation to the angle-irons 24.

Assuming the window to be open as illustrated in Fig. 5, and the spring 17 adjusted by operation of the spindle 19 to predetermine the initial temperature at which the damper shall begin to open, as the temperature within the room rises the expansible and collapsible vessel 9 tends to expand. Such expansion, however, is opposed by the tension of the spring 17 until that temperature is reached at which if has been predetermined the thermosensitive means shall assume control of the damper. Thereafter, a further rise of temperature within the room causes an expansion of the vessel 9, with a resultant movement of the lever 13 (or 13') 105 against the tension of the spring 17, operating bar 8 to move shutters 5 about their pivots and open the passage through the frame 1. A further increase in temperature results in a further increase in the opening of the shutters, a decrease in temperature resulting in a closing of the shutters. Thereby, the amount of air flowing through the 110 passage provided by the frame 1 is automatically controlled in accordance with the needs of the room, as determined by the temperature of the air in the same. Furthermore, owing to the construction and arrangement of this ventilating device, it will 115 be perceived that there is no interference with the opening and closing of the window.

While the ventilating device has been 130

shown as positioned at the lower end of the window, it is apparent it could equally well be positioned at the top of the window, or two ventilating devices could be provided, 5 one at the bottom and one at the top. While the frame has been shown as snugly fitting in the window casing, it will be understood that this is not essential, as the frame may be made of any shorter length and the space 10 between the end of the frame and the window casing left open, or the frame may be provided with an adjustable extension plate for closing this space. It will also be apparent that the height of the frame constitutes 15 no part of the invention; for the same may be selected in accordance with the maximum quantity of air that it is desired shall flow through the ventilating device when the damper device is wide open.

20 What is claimed is:

1. A self-contained, portable, automatic ventilating-device comprising a frame adapted to be positioned at the aperture provided by an open window, said frame 25 providing an air-passage therethrough, a damper device for controlling the flow of air through said passage, and a thermosensitive device carried by said frame and operatively connected to said damper device, 30 said frame and the parts carried thereby constituting a complete, automatic ventilating unit.

2. A self-contained, portable, automatic ventilating-device comprising a frame 35 adapted to be positioned at the aperture provided by an open window without interfering with the opening and closing of the window, said frame providing an air-passage therethrough, a damper device for 40 controlling the flow of air through said passage, and a thermosensitive device carried by said frame and operatively connected to said damper device, said frame and the parts carried thereby constituting a complete 45 automatic ventilating unit.

3. A self-contained, portable, automatic ventilating-device comprising a frame adapted to be positioned at the aperture provided by an open window, said frame 50 providing an air-passage therethrough, a damper device for controlling the flow of air through said passage, and a thermosensitive device carried by said frame and subjected to the temperature of the air in the 55 room, said thermosensitive device being operatively connected to said damper device, said frame and the parts carried thereby constituting a complete, automatic ventilating unit.

60 4. A self-contained, portable, automatic ventilating-device comprising a frame adapted to be positioned at the aperture provided by an open window, said frame 65 providing an air-passage therethrough, a sealing strip carried by said frame for pre-

venting the leakage of air therepast, a damper device for controlling the flow of air through said passage, and a thermosensitive device carried by said frame and operatively connected to said damper device, 70 said frame and the parts carried thereby constituting a complete, automatic ventilating unit.

5. A self-contained, portable, automatic ventilating-device comprising a frame 75 adapted to be positioned at the aperture provided by an open window, said frame providing an air-passage therethrough, means for mounting said frame adjustably in position, a damper device for controlling the 80 flow of air through said passage, and a thermosensitive device carried by said frame and operatively connected to said damper device, said frame and the parts carried thereby constituting a complete, automatic 85 ventilating unit.

6. A self-contained, portable, automatic ventilating-device comprising a frame adapted to be positioned at the aperture provided by an open window, said frame 90 providing an air-passage therethrough, a damper device for controlling the flow of air through said passage, a thermosensitive device carried by said frame and operatively connected to said damper device, and means 95 for adjusting said thermosensitive device to predetermine the temperature at which the same begins to operate said damper device, said frame and the parts carried thereby constituting a complete, automatic ventilating 100 unit.

7. A self-contained, portable, automatic ventilating-device comprising a frame adapted to be positioned at the aperture provided by an open window, said frame 105 providing an air-passage therethrough, a damper device for controlling the flow of air through said passage, a thermosensitive device carried by said frame and operatively connected to said damper device, and an enclosure for said thermosensitive device provided with apertures for the admission of the air of the room thereto, said frame and the parts carried thereby constituting a complete, automatic 110 ventilating unit.

8. A self-contained, portable, automatic ventilating-device comprising a frame adapted to be positioned at the aperture provided by an open window, said frame providing an air-passage therethrough, a damper device for controlling the flow of air through said passage, a thermosensitive device carried by said frame and operatively connected to said damper device, and means to insulate said thermosensitive device from the temperature of the air flowing through said passage, said frame and the parts carried thereby constituting a complete, automatic 115 ventilating unit.

9. A self-contained, portable, automatic 120

ventilating - device comprising a frame adapted to be positioned at the aperture provided by an open window, said frame providing an air-passage therethrough, a 5 damper device for controlling the flow of air through said passage, and an expansible and collapsible vessel charged with a volatile thermosensitive fluid carried by said frame and operatively connected to said damper 10 device, said frame and the parts carried thereby constituting a complete, automatic ventilating unit.

10. A self-contained, portable, automatic ventilating - device comprising a frame 15 adapted to be positioned at the aperture provided by an open window, said frame providing an air-passage therethrough, a damper device for controlling the flow of air through said passage, an expansible and collapsible vessel charged with a volatile thermosensitive fluid carried by said frame and operatively connected to said damper device, 20

a spring opposing expansion of said vessel, and means for adjusting said spring to pre-determine the temperature at which said vessel begins to expand, said frame and the parts carried thereby constituting a complete, automatic ventilating unit. 25

11. A self-contained, portable, automatic, ventilating - device comprising a frame 30 adapted to be positioned at the aperture provided by an open window, said frame providing a horizontal air-passage extending directly therethrough, a damper device for controlling the flow of air through said 35 passage, and a thermosensitive device carried by said frame and operatively connected to said damper device, said frame and the parts carried thereby constituting a complete, automatic ventilating unit. 40

In testimony whereof I have signed this specification.

WESTON M. FULTON.
